LOOP-FORMING AND ATTACHING DEVICE

John D. Karle, Roselle Park, N. J., assignor to
The Singer Manufacturing Company, Elizabeth, N. J., a corporation of New Jersey

Application May 13, 1936, Serial No. 79,430

23 Claims. (Cl. 112—9)

This invention relates to sewing machines and it has as its primary object to provide improved means, preferably in the nature of an attachment designed readily to be applied to a conventional domestic sewing machine, to adapt it to produce ornamental effects and products not generally produced on sewing machines.

Stated more specifically, this invention has as an object to provide an improved attachment for sewing machines which will act automatically and continuously, during normal operation of the machine, to form loops of wool yarn, or the like, in advance of the stitching point, to feed the yarn loops to the stitching mechanism, by which they are attached at one end to an underlying base material, and automatically to sever the opposite ends of the loops, the severed ends thereupon standing erect and producing a soft, nappy surface such as is particularly desirable in rugs.

This product, however, is not new, as heretofore it has been made by manually wrapping strands of wool yarn about a forked supporting member, stitching the loops thus formed to a base material, withdrawing the forked member and manually severing one end of the attached yarn loops, as by means of a pair of shears, or by a cutter attached to the forked member. This manual operation, however, was slow and tedious and the quality of the product depended largely upon the skill of the operator.

This invention has as a further object to render available a simple and efficient device which readily may be attached to a conventional family sewing machine and which, when so attached, will automatically and rapidly produce the above described product in uniform high quality, and without requiring the exercise of any great amount of skill or ingenuity on the part of the operator.

Obviously differently colored yarns may be used in various parts of the work, thereby producing color effects or patterns in the finished product, which is greatly desired in rugs, etc.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the accompanying drawings Figure 1 is a front elevation of the improved attachment, one por-

tion of which is shown in elevation and another portion in section.

Fig. 2 is a left side view, partly in section, of Fig. 1.

Fig. 3 is a horizontal sectional view, substantially on the line 3—3 of Fig. 1 showing the major portion of the attachment in plan view.

Fig. 4 represents a central vertical section substantially on the line 4—4 of Fig. 1.

Fig. 5 is a sectional view substantially on the line 5—5 of Fig. 2.

Fig. 6 is a view similar to Fig. 5 but showing, in addition, the base material to which the yarn loops are stitched and the action of the yarn-winding and loop-severing means.

Fig. 7 is a disassembled perspective view of elements of the yarn-winding and loop-supporting means, later to be described.

Fig. 8 is a perspective view of a portion of one product produced by a sewing machine equipped with the present improved attachment.

Fig. 9 is a detail perspective view illustrating the action of a yarn deflecting finger, later to be described.

Referring more specifically to the drawings, the invention is disclosed as applied to a sewing machine including a head 1 carrying a presser-bar 2, a reciprocating needle-bar 3 carrying an eye-pointed needle 4, a work-plate 5, a throat-plate 6, a slide-plate 7, and feeding mechanism including a vertically and horizontally movable feed-dog 8. Cooperating with the needle, in the formation of stitches, is a suitable loop-taker (not shown) located beneath the throat-plate.

As hereinbefore stated loops *l* of a wool yarn *y*, or the like, are automatically and continuously formed in advance of the stitching point and parallel rows of these loops are stitched successively to each other or to a base material *m*, as shown most clearly in Figs. 6 and 8, as the loops and the material are fed past the stitching point by the feed mechanism.

The improved device which forms the yarn loops comprises a main supporting frame 9 adapted to be removably secured to the presser-bar as by means of a screw 10. This frame includes a horizontal forwardly extending portion 11 and a vertically arranged portion 12 which supports elements of the winding mechanism, later to be described. To the end that the device may be attached to various types of domestic sewing machines, the shank of the frame 9 is provided with a plurality of apertures 9^x through any one of which the screw 10 may be passed.

Secured to the under side of the portion 11 is a

presser-plate 13 which overlies the base material *m* and normally holds it down upon the throat-plate, so that it will be advanced periodically by the feed-dog 8, in the usual manner. The edge 5 of 13^x of the plate 13 serves as a guide for the previously stitched row of loops, whereby the successive rows are spaced uniformly.

Within a circular cavity 12^a, formed in the portion 12 of the frame, is secured a hardened metal wear-ring 14, which, as shown most clearly in Fig. 4, together with the portion 12, provides a bearing for a circular disk 15 which constitutes one element of a rotary yarn-winding member or flier *f*. The flier includes, in addition to the disk 15, a ratchet-wheel 16 provided with five ratchet teeth 16^a, a tubular hub 17 to which both of the members 15 and 16 are secured, and a yarn-carrying tube 18 which extends through both of said members. Yarn is led to the tube 18, from 10 a suitable source of supply, through a so-called self-threading guide member 19, supported by the portion 12 of the main frame, and having its guiding eye coaxial with the center of the rotary winding disk 15.

25 Journaled within the hub 17, and held therein, by a nut 20, is a spindle 21, having an enlarged shoulder 21^a and a head 21^b. Secured to the head 21^b, as by a screw 22, is a sheet-metal arbor 23 about which the loops *l* of the yarn are 30 wound by the rotary motion of the flier *f*. Intermediate the disk 15 and the arbor 23 the portion 21^a of the spindle 21 carries a cylindrical member, or drum, 24 which is cut away at 24^a to receive the shank of the arbor. The upper end 35 23^a of the arbor is bent forwardly and is fitted within the member 24, as shown most clearly in Fig. 4. The member 24 has a portion of its periphery beveled at 24^b to merge into the face of the arbor thereby to assist in placing the yarn 40 loops about the arbor.

The flier *f* is given a partial rotation, of 72 degrees, at each reciprocation of the needle-bar. Thus in five reciprocations of the needle-bar the flier is given one complete rotation thereby placing the yarn loop completely around the arbor 23. This step-by-step rotation of the flier is effected by the downward movement of an actuating pawl 25 pivotally mounted on a stud 27 carried by a bracket 26, removably secured to the needle-bar 3. The pawl is formed with a pointed end 25^a which operates in a vertically arranged slot 12^c formed in the portion 12 of the main frame 9 and engages the ratchet-teeth 16^a of the disk 16. A coil spring 28, surrounding the stud 27 and having one end 28^a engaging the pawl 25 and its other end 28^b fitted within a groove in the bracket 26, normally biases the pawl in one direction to maintain the end 25^a thereof in contact with the ratchet disk 16. Thus at each downward movement of the needle-bar the pawl 25 effects a partial rotation of the flier *f*. A spring-pressed retaining pawl 29, carried by a stud 30, secured to the disk 16 is adapted to engage teeth 31 provided by a face-plate 32 secured to the portion 12, thereby to prevent retrograde movement of the flier. The face-plate 32 overlies the marginal portion of the disk 16 and thus retains the flier in the cavity 12^a in the main frame.

As shown most clearly in Figs. 3, 4 and 7 the 70 arbor 23 is curved downwardly and rearwardly toward the needle and is provided at one side with a loop-supporting finger 23^b which temporarily retains one end of the loop placed thereabout by the flier. At its opposite side the arbor is formed 75 with an extension 23^c which underlies a portion

of the main frame 9 and preferably is secured thereto as by a screw 33. This extension 23^c may also serve as a stationary cutter-blade as later will be described.

From the foregoing it will be understood that, 10 during normal running of the machine, loops of 15 yarn will be wound around the arbor 23 and, due to the shape and arrangement of the arbor, those loops will tend to slip down into the path of the needle 4. To the end that the loops will be presented to the needle uniformly, positively actuated loop-feeder fingers 33 have been provided. These fingers are formed as a part of a plate 34 pivotally mounted at 34^x on the bracket 26, carried by the needle-bar. A coil spring 35, surrounding 15 the pivot 34^x, engages the plate 34 and normally holds it in the position shown in Fig. 2, i. e., in contact with a stop 36 provided by the bracket 26 and with the fingers 33 in vertical alignment with the upper curved portion 23^a of the arbor. 20 As the needle-bar descends the spring-pressed fingers 33 slide downwardly over the face of the arbor and cause the yarn loops to be forced downwardly thereon as shown in Figs. 2 and 6. To insure that the fingers will positively feed the loops 25 and not ride over the same during the downward movement of the fingers, the arbor 23 is provided with apertures 23^d into which the fingers 33 enter during their downward movement while the yarn loops are supported by the walls at 30 opposite sides of the apertures 23^d.

As the yarn loops are fed downwardly on the arbor they are stitched to the body material *m* by the stitch-forming mechanism, as shown in Figs. 6 and 8, and fed past the stitching point by the 35 action of the feed-dog 8. Those ends of the loops which were supported on the finger 23^b of the arbor eventually slide off the free end thereof and pass, uncut, beneath the supporting shank of the main frame 9 through an unobstructed 40 passage indicated as *p* in Figs. 2, 3 and 4. Those ends of the loops which surround the opposite side of the arbor are fed along the portion 23^c and are severed by cutting mechanism, later to be described, so that the severed ends may pass 45 beyond the end of the portion 23^c when it is attached to the main frame. Although the drawings illustrate the preferred form of the invention it is to be understood that, if desired, the portion 23^c may be detached from the main frame and 50 the cutting mechanism may be omitted, whereupon neither end of the loops will be severed.

The means for severing one end of the yarn loops preferably comprises a vibratory cutter-actuating lever 37 fulcrumed at 38 on a bracket 55 39 secured to the face-plate 32, by screws 40. At one end, the lever 37 carries a blade 41 having a cutting edge 41^x which cooperates with an underlying stationary cutting edge 23^x formed on the extension 23^c of the arbor. At its opposite end 60 the lever 37 has a curved upwardly extending portion 37^a, the inner surface 37^b of which is normally maintained in the path of a roller 42 carried by the stud 30 which supports the retaining pawl 29. During each rotation of the flier *f* the 65 roller 42 engages the surface 37^b of the cutting lever and swings it clockwise, as viewed in plan, from the position shown in full lines in Fig. 3 to the position indicated by dotted lines. This movement of the lever causes the cutting edge 70 41^x of the cutter-blade to cooperate with the cutting edge 23^x and sever one of the yarn loops surrounding the portion 23^c of the arbor. A leaf spring 43 secured to the cutter-blade 41 by screws 44 (which also serve to secure the blade to the 75

cutter lever) bears upon the free end of the movable cutter-blade and yieldingly holds it into cutting contact with the stationary cutter-blade.

The retractive movement of the cutter-lever, i. e., the movement from the dotted line position to the full line position in Fig. 3, is effected by the action of a cutter-return lever 45 fulcrumed at 46 on the upright portion 12 of the main frame 9. This lever is formed with one arm 45^a, which abuts an upturned portion 37^c of the cutter-lever 37, and a second arm 45^b which, during rotation of the fler is engaged by a roller 47 loosely journaled on the yarn-carrying tube 18. This roller tracks an annular groove 24^d in the drum 24 and in its rotation engages and swings the lever 45 counter-clockwise, as viewed in Fig. 5, thereby causing the arm 45^a to swing the cutter-lever to its retracted position.

As shown by Fig. 8, the severed ends of the loops stand upright and produce a soft nappy surface. By successively stitching parallel rows of the yarn loops to a base material and severing one end of the loops, as above described, an ornamental product may be obtained. This product is used rather extensively in the making of rugs. Various color effects and patterns may be obtained by the use of differently colored yarns.

To prevent the severed ends of the loops of a previously stitched row from being inadvertently engaged by the cutter during a subsequent operation, the cutter-lever 37 is formed with a guard plate or finger 37^e (Fig. 3) which overlies the severed loops of a preceding row and holds them down out of the path of the cutter.

Having thus set forth the nature of the invention, what I claim herein is:—

1. An attachment for sewing machines comprising a main frame adapted to be secured to the presser-bar of the machine, an arbor carried thereby, means carried by said main frame and actuated by the reciprocations of the needle-bar for winding loops of yarn about said arbor and for presenting said loops to the stitching mechanism for attachment to a base material located beneath said main frame, and automatically actuated means for severing one end of said loops after they have been stitched to the base material.

2. An attachment for sewing machines comprising a main frame adapted to be secured to the presser-bar of the machine, an arbor carried thereby, and means carried by said main frame and actuated by the reciprocations of the needle-bar for winding loops of yarn about said arbor and for presenting said loops to the stitching mechanism.

3. An attachment for sewing machines comprising a main frame adapted to be secured to the presser-bar of the machine, a downwardly and rearwardly inclined arbor carried thereby, means including a rotary yarn carrying element carried by said main frame and actuated by the reciprocations of the needle-bar for winding loops of yarn about said arbor and for presenting

said loops to the stitching mechanism for attachment to a base material located beneath said main frame, and means actuated by the reciprocations of the needle-bar for severing one end of said loops after they have been stitched to the base material.

4. An attachment for sewing machines comprising a main frame adapted to be secured to the presser-bar of the machine and provided with a cavity, an arbor carried by said frame, means including a rotary yarn-carrying fler journaled in

said cavity and actuated by the reciprocations of the needle-bar for winding loops of yarn about said arbor, means for presenting said loops to the stitching mechanism, and automatically actuated means for severing one end of said loops after they have been stitched.

5. An attachment for sewing machines comprising a main frame adapted to be secured to the presser-bar of the machine, an arbor carried thereby, means carried by said main frame and actuated by the reciprocations of the needle-bar for winding loops of yarn about said arbor and for presenting said loops to the stitching mechanism for attachment to a base material located beneath said main frame, and means including a fixed blade and a cooperating horizontally movable blade actuated from the reciprocatory movements of the needle-bar for severing one end of said loops after they have been stitched to the base material.

6. An attachment for sewing machines comprising a main frame adapted to be secured to the presser-bar of the machine, an arbor carried thereby, means carried by said main frame and actuated by the reciprocations of the needle-bar for winding loops of yarn about said arbor, and means for advancing said loops along said arbor to the stitching mechanism.

7. An attachment for sewing machines comprising a main frame adapted to be secured to the sewing machine, an arbor carried thereby, means carried by said main frame and actuated by the reciprocations of the needle-bar for winding loops of yarn about said arbor, means including reciprocatory feeder fingers carried by the needle-bar of the machine and engaging the loops held upon said arbor to advance said loops to the stitching mechanism, and means for severing one end of said loops after they have been stitched.

8. An attachment for sewing machines comprising a main frame, means to secure said frame to a sewing machine, an arbor supported from said main frame, and means including a rotary yarn-carrying element carried by said main frame and actuated by the reciprocations of the needle-bar for forming yarn loops about said arbor and for presenting said loops to the stitching mechanism.

9. An attachment for sewing machines having stitching mechanism, comprising a main frame, means to secure said frame to a sewing machine, an arbor supported from said main frame, means including a rotary yarn carrying element carried by said main frame and actuated by the reciprocations of the needle-bar for forming yarn loops about said arbor and for presenting said loops to the stitching mechanism and automatically actuated means, located to one side and rearwardly of the stitching mechanism and including a stationary cutter-blade and a cooperating movable cutter-blade actuated by the rotary movements of said rotary yarn-carrying element, for severing one end of said loops after they have been stitched.

10. An attachment for domestic sewing machines comprising a main frame adapted to be secured to the presser-bar of the machine, an arbor carried thereby, a rotary yarn-carrying element carried by said main frame and rotated by the reciprocations of the needle-bar for winding loops of yarn about said arbor and for presenting said loops to the stitching mechanism, and means actuated by the rotation of said yarn-carrying element for severing one end of said loops after they have been stitched.

11. An attachment for sewing machines comprising a main frame adapted to be secured to the presser-bar of the machine, a downwardly curved and rearwardly extending bifurcated sheet metal arbor carried thereby, one arm of said arbor affording a stationary cutter-blade, means carried by said main frame and actuated by the reciprocations of the needle-bar for winding loops of yarn about said arbor and for presenting said loops to the stitching mechanism, and a movable cutter-blade supported by said frame and actuated by the reciprocations of said needle-bar and cooperating with said stationary cutter-blade for severing one end of said loops after they have been stitched. 5
12. An attachment for sewing machines comprising a main frame, means to secure said frame to a sewing machine, means including a rotary element actuated by the reciprocations of the needle-bar for forming loops of yarn and for presenting said loops to the stitching mechanism, a stationary cutter-blade carried by said frame, a movable cutter-blade pivotally mounted on said frame and cooperating with said stationary blade to sever the yarn loops after they have been stitched, means actuated by the rotary movement of said loop-forming means to give to said movable cutter-blade its cutting stroke, and other means actuated by said loop-forming means 20 to give the movable cutter-blade its retractive stroke. 25
13. An attachment for conventional domestic sewing machines comprising a main frame adapted to be secured to the presser-bar of the machine, means including a rotary element carried by said main frame and actuated by the reciprocations of the needle-bar for forming loops of yarn and for presenting said loops to the stitching mechanism, a horizontally disposed stationary cutter-blade carried by said frame, a horizontally movable oscillatory cutter-lever fulcrumed on said frame and carrying a cutter-blade which cooperates with said stationary cutter-blade to sever the yarn loops after they have been stitched, a roller carried by said rotary element adapted to engage said cutter-lever at one side of its fulcrum to swing said lever in one direction, a cutter-return lever pivotally mounted on said main frame and having an arm in contact with said cutter-lever at the opposite side of its fulcrum, and a roller carried by said rotary element and adapted to actuate said cutter-return lever to cause it to retract said cutter lever. 35
14. An attachment for sewing machines comprising a main frame adapted to be secured to the presser-bar of the machine, a downwardly curved and rearwardly extending arbor carried thereby, means carried by said main frame and actuated by the reciprocations of the needle-bar for winding loops of yarn about said arbor, means including loop-feeder fingers carried by the needle-bar and cooperating with said arbor to advance the yarn loops to the stitching mechanism, and automatically actuated means for severing one end of said loops after they have been stitched. 55
15. An attachment for sewing machines comprising a main frame adapted to be secured to the presser-bar of the machine, an arbor carried thereby, means carried by said main frame and actuated by the reciprocations of the needle-bar for winding loops of yarn about said arbor and means including loop-feeder fingers carried by the needle-bar and cooperating with said arbor 70
- to advance the yarn loops along said arbor to the stitching mechanism. 75
16. An attachment for sewing machines comprising a main frame adapted to be secured to the presser-bar of the machine, means carried by said main frame and actuated by the reciprocations of the needle-bar for forming yarn loops and for presenting said loops to the stitching mechanism, means carried by said main frame for severing ends of said loops after they have been stitched, and guard means overlying previously stitched loops to hold them out of contact with said loop-severing means. 80
17. The combination with a sewing machine having a presser-bar, stitch-forming mechanism including a reciprocatory needle-bar and a needle carried thereby, of means including a rotary yarn winding device carried by the presser-bar and rotated by the reciprocations of the needle-bar for forming loops of yarn in advance of the stitching point, and means for advancing said loops to the stitching mechanism. 15
18. The combination with a sewing machine having a presser-bar, stitch-forming mechanism including a reciprocatory needle-bar and a needle carried thereby, of means including a rotary yarn winding device carried by the presser-bar and rotated by the reciprocations of the needle-bar for forming loops of yarn in advance of the stitching point, means for advancing said loops to the stitching mechanism, and means actuated by the rotation of said winding device to sever one end of the stitched loops. 20
19. The combination with a sewing machine having a presser-bar and stitch-forming mechanism including a reciprocatory needle-bar and a needle carried thereby, of an arbor located in advance of the stitching point, means including a rotary yarn winding device carried by the presser-bar and rotated by the reciprocations of the needle-bar for forming loops of yarn about said arbor, and means for advancing said loops along said arbor to the stitching mechanism. 25
20. The combination with a sewing machine having a presser-bar and stitch-forming mechanism including a reciprocatory needle-bar and a needle carried thereby, of a loop-supporting arbor sustained by said presser-bar, means including a rotary yarn winding device carried by the presser-bar and rotated by the reciprocations of the needle-bar for forming loops of yarn about said arbor in advance of the stitching point, means for advancing said loops along said arbor to the stitching mechanism, and means for severing one end of the stitched loops. 45
21. A rug making attachment for domestic sewing machines comprising a main frame adapted to be attached to a conventional presser-bar, a loop-supporting arbor carried by said frame, a rotary flier journaled in said frame and having a yarn-guiding eye, means including a ratchet mechanism actuated by a conventional reciprocatory needle-bar for rotating said flier and yarn-guiding eye about one end of said arbor thereby to place loops of yarn thereabout, means for advancing said loops along said arbor to the stitching mechanism, and means for severing one end of the attached yarn loops. 55
22. A rug making attachment for domestic sewing machines comprising a main frame adapted to be attached to a conventional presser-bar and provided with a circular cavity and a connecting vertically disposed slot, a rotary yarn-carrying flier journaled in the cavity in said frame and including a ratchet wheel, a co- 70

operating pawl carried by the conventional reciprocal needle-bar and projecting through said vertically disposed slot into engagement with said ratchet-wheel whereby the flier is given intermittent rotary motions by the reciprocations of the needle-bar, an arbor supported coaxial with said flier and about which yarn loops are placed by the rotation of the latter, means for advancing said loops along said arbor to the stitching mechanism, and means for severing one end of the attached yarn loops.

10 23. A rug making attachment for domestic sewing machines comprising a main frame

adapted to be attached to a conventional presser-bar, a loop-supporting arbor carried by said frame and providing a stationary cutter blade, a rotary flier journaled in said frame and having a yarn-guiding eye, means including a ratchet mechanism actuated by a conventional reciprocal needle-bar for rotating said flier and yarn-guiding eye about one end of said arbor thereby to place loops of yarn thereabout, means for advancing said loops along said arbor to the stitching mechanism, and means for severing one end of the stitched yarn loops.

JOHN D. KARLE.
